CLAIM

The ornamental design for electric ice-scraping machine, as shown and described.

DESCRIPTION

FIG. 1 is a perspective view of electric ice-scraping machine showing our new design thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an exploded view of the design of FIG. 1.

The surfaces or portions of the article not shown in the drawing or described in the specification form no part of the claimed design.
